UNITED STATES PATENT OFFICE

165,197

EDIBLE SHELL OR THE LIKE

Eleanor A. Thomas, Ruxton, Md.

Application October 3, 1950, Serial No. 12,427

Term of patent 14 years

(Cl. D8—1)

To all whom it may concern:

Be it known that I, Eleanor A. Thomas, a citizen of the United States, residing at Ruxton, State of Maryland, have invented a new, original, and ornamental Design for an Edible Shell or the like, of which the following is a specification, reference being had to the accompanying drawings, forming a part hereof, in which:

Fig. 1 is a top plan view of an edible shell, showing my new design,

Fig. 2 is a bottom plan view thereof,

Fig. 3 is a front elevational view thereof, and

Fig. 4 is a side elevational view thereof.

I claim:

The ornamental design for an edible shell or the like, substantially as shown.

ELEANOR A. THOMAS.
